Patented Feb. 19, 1918.

UNITED STATES PATENT OFFICE.

FRANK A. HAUGH, OF ELDORADO, KANSAS, ASSIGNOR TO CAMDON L. BLOOM, OF INDEPENDENCE, KANSAS.

UNDERREAMER.

1,257,226.

Specification of Letters Patent. Patented Feb. 19, 1918.

Application filed March 31, 1917. Serial No. 158,886.

To all whom it may concern:

Be it known that I, FRANK A. HAUGH, a citizen of the United States, residing at Eldorado, in the county of Butler and State 5 of Kansas, have invented a new and useful Underreamer, of which the following is a specification.

This invention relates to underreamers, or expanding bits for underreaming beneath 10 the casing in drilling wells.

An object of the invention is to provide an improved construction which can be inserted into and withdrawn from wells, or other borings, through their casings, without damaging or breaking off the cutters or other parts and so leaving them in the well, and without damaging the casings.

Another object of the invention is to provide a construction having cutters which can 20 be easily moved to and from operative position, held rigidly in operative position, or quickly removed and replaced, if desired.

Another object of the invention is to provide a construction having a plurality of 25 series of superimposed cutters provided with automatic mechanism common to the series for holding them rigidly in projected or operative position or to allow them to move into inoperative position.

30 In the accompanying drawing, I have illustrated one embodiment of the invention, in which:

Figure 1 is a longitudinal view of the underreamer.

35 Fig. 2 is a longitudinal sectional view of the same on a larger scale than Fig. 1, showing the cutters in operative position.

Fig. 3 is a longitudinal sectional view on a 40 larger scale than Fig. 1, showing the underreamer in the well casing and the cylindrical ring used in holding trips in while the underreamer is being moved to the bottom of the casing.

Fig. 4 is a cross sectional view on the line 45 4—4 of Fig. 2.

Fig. 5 is a cross sectional view on the line 50 5—5 of Fig. 2.

Fig. 6 is a cross sectional view on the line 6—6 of Fig. 2.

55 Fig. 7 is a detail view of a portion of the underreamer, showing the slot in which the trips work.

Fig. 8 is a detail view, partly in section, of one of the cutters.

55 The underreamer of the embodiment of

the invention herein shown and described comprises a body portion or cylinder 1 having a chamber or longitudinal bore 2 at its lower end. The walls of the longitudinal bore 2 are provided with a lower series and 60 an upper series of circumferentially arranged slots 3 extending longitudinally of the casing 1. The slots of one series, as will be seen from a comparative inspection of Figs. 5 and 6 and from Fig. 1, are staggered 65 with relation to the slots of the other series. As will be seen from an inspection of Figs. 2 and 3, the upper and lower boundaries or walls 4 of the slots are beveled and converge 70 outwardly for a purpose to be hereinafter described.

Mounted within each slot is a cutter 5. Each cutter at its upper end has a projecting lug 6 having a transversely extending hole 7 therethrough. A radially extending 75 pin 8 is arranged immediately above each slot, projects inwardly into the bore 2 and supports the cutter by extending through the hole 7 of the lug 6. This cutter has no other means of support and can be easily 80 disengaged from the pin when so desired. The inner edge 9 of each cutter is inclined and extends downwardly toward the center of the cylinder 1. The outer edge 10 of each cutter is also inclined and extends downwardly and outwardly when in projected position. Each cutter at the top and bottom is provided with edges 11 and 12 which are beveled and converge outwardly, as clearly 85 shown in Fig. 8, in order to engage and fit 90 the beveled portions 4 of the slot whereby when the cutters are pressed outwardly, they will be rigidly supported and securely retained within their slots. The lower inner portion of each cutter has a projection or 95 lug 13 constituting a stop, which, when the cutters are projected, as shown in Fig. 2, engages the cylinder 1 immediately below the slot. The outer lower portion of each cutter is notched at 14 which insures a better 100 cutting effect.

A plunger rod 15 is provided within the underreamer and reciprocates longitudinally therein. A tapered plunger head 16 is threaded, as shown at 17 to the lower end 105 of the rod and is arranged to engage the inner edges 9 of the lower series of cutters. Slidably mounted on the rod 15 above and spaced from the lower plunger head 16 is a tapered plunger head 18 abutting a 110

suitable collar 19 upon the plunger rod. Communicating and aligned with the bore or chamber 2 is a similar bore 20 of reduced diameter constituting a housing for a spring 21 which is interposed between the upper portion of the plunger head 18 and the upper end of the bore 20. This spring acting upon the plunger head 18 tends to keep both heads depressed and in the position shown in Fig. 2, whereby they engage the inner edges of the cutters and force them into the slots and hold them rigidly therein and in projected position. The plunger heads also serve, when in raised position, as shown in Fig. 3, to retain the cutters upon the pins 8 for, normally, the heads do not rise above the position shown in Fig. 3, their lower ends being in front of the holes 7 of the cutters retaining the latter upon the pins 20 but allowing the cutters to swing inwardly without trouble.

When it is desired to remove one or more of the cutters, the plungers can be moved slightly above the position shown in Fig. 25 3. The outer portion of the cutter is grasped and moved slightly inwardly to disengage the same from the pin. The cutter is then moved upwardly swinging the lower end outwardly whereby the cutter 30 may be easily removed through the slot.

I have also provided means for automatically raising the plungers to allow the cutters to swing inwardly when they engage the hole or well casing as the underreamer is being raised out of the hole through the casing thereof. For this purpose the upper portion of the cylinder 1 is provided with a diametrically extending slot 22 into which the upper end of the 40 plunger rod extends. A cross arm 23 is fixed to the upper end of the plunger rod and held in position thereon by means of a nut 24. A pair of trips 25 are mounted to swing out of and into each end of the slot 45 22 at opposite sides of the body of the underreamer. Each trip is beveled at each end, as shown at 26 and has a longitudinal slot 27 therethrough, see Fig. 7. In order to connect each trip to the body of the 50 underreamer, a link 28 is pivoted at its outer end 29 to the lower end of the trip within the slot 27. The inner end 29a is pivoted between the walls of the slot 22. Two bell crank levers 30 having spacing 55 bearings 30a are pivoted intermediate their ends, as indicated at 31 between the walls of the body of the underreamer, and at their outer ends 32 project into the slots 27 and are pivoted to the trips at their upper 60 ends. These levers are arranged in cross relation to each other, as shown in Figs. 2 and 3 and upon opposite sides of the plunger rod, as shown in Figs. 4 and 7, and have their inner ends engaging the cross 65 bar 23.

Threaded within the head of the underreamer, as shown at 33, is a bit or cutter 34 having a knife edge at its lower end. This bit co-operates with the adjustable cutters. This bit is for the purpose of reaming holes that are caving in and bridging over, as one can by means of it get down into the cave or bridge and ream the hole without it being necessary to change tools. By arranging the cutters in superimposed 70 series, the upper series of cutters will cut away any projections which are missed by the lower series and enlarge the hole made by the bit 34 in order that the well casing 75 may be easily placed in position. 80

For purposes of illustration, the well casing is illustrated in Fig. 3 at 35, showing the underreamer within the upper portion of the same and in position to be lowered into the hole or well. A cylindrical ring 36 85 encircles the body of the underreamer and incloses the trips 25 holding them in non-projected position. The ring 36 is of substantially the same diameter as the casing 35 and as the underreamer is lowered, it will be seen that the lower edge of the ring will engage the upper edge of the casing, as shown at 37 and will be held against further downward movement, and will be finally disengaged from the underreamer entirely 90 when the latter has completely entered the casing. However, when the underreamer is within the casing, the walls thereof serve to retain the trips in their non-projected position. It will be noticed that when the trips 100 are in this latter position that the ends of the bell crank levers will have moved upwardly moving the plunger rod with the plunger heads out of engagement with the inner edges of the cutters, allowing the lower 105 ends thereof to swing inwardly out of the way. It is for this reason that the outer edges of the cutters are more or less beveled, as shown at 10 in order that as they engage the casing 35 of the hole or well they will be moved out of the way. As soon as the trips 25 project beyond the lower end of the casing 35, the spring 21 is allowed to again force the plunger heads downwardly 110 between the inner edges of the cutters and force them outwardly and then the reaming or boring operation is continued or begun. 115

When it is desired to pull the underreamer out and back up through the casing 35, the beveled edges 26 of the trips engage the lower end of the casing 35 and the trips will be moved inwardly into the position shown in Fig. 3, thereby raising the plunger up out of the way of the cutters. When the portions of the underreamer having the cutters 120 projecting therefrom enter the casing 35, the latter will cam the cutters inwardly out of the way whereby the underreamer can be pulled up through the casing without danger 125 of the cutters marring the same in any re- 130

spect. At the same time, the cutters themselves are fully protected against breakage or disengagement. The cutters being suspended from their upper ends and flaring downwardly have low centers of gravity whereby there is always a natural tendency for the same to swing inwardly.

While I have shown and described one embodiment of my invention, it is to be understood that I do not desire to be limited to the details of construction herein shown and described, for obvious modifications will be apparent to anyone skilled in the art.

What is claimed is:—

- 15 1. In an underreamer, a cylinder provided with a lower series and an upper series of circumferentially arranged longitudinally extending slots, a cutter movably mounted in each slot, a plunger having heads thereon adapted to engage the cutters to simultaneously actuate the upper and lower series thereof, and means for actuating said plunger to allow the cutters to move inwardly or to hold the same rigidly projected in their slots.
- 20 2. In an underreamer, a cylinder having circumferentially arranged slots having beveled upper and lower ends which converge outwardly, cutters detachably held in the cylinder and having corresponding beveled ends adapted to engage the beveled ends of the slots, means detachably connecting the cutters to the cylinder and a plunger having a head adapted to engage the inner edges of the cutters to hold them in projected position and prevent accidental detachment thereof.
- 25 3. In an underreamer, a cylinder having a plurality of slots therein, an inwardly projecting pin at the upper end of and immediately above each slot, cutters loosely and removably attached at their upper ends to said pins and adapted to be moved through said slots to extends beyond the cylinder or to be moved to a position within the cylinder, and a plunger having a head adapted to force the cutters outwardly and to hold the same rigidly within the slots and movable upwardly to allow the cutters to swing inwardly, said plunger serving to retain the cutters upon said pins.

- 40 4. In an underreamer, a cylinder having a plurality of longitudinally extending slots spaced circumferentially therearound and having beveled upper and lower edges converging outwardly, a cutter loosely connected to said cylinder at its upper end immediately above each slot and provided with corresponding beveled portions adapted to engage the beveled portions of the slot, the lower end of each cutter being provided with a stop, the outer edges of the cutters extending downwardly and outwardly constituting cam surfaces, the inner edges extending downwardly and inwardly, and a plunger for forcing said cutters outwardly.

5. In an underreamer, a body having slots tapering outwardly therein, cutters having portions correspondingly shaped to said slots and adapted to engage therewith, means for detachably connecting the cutters to the body above the slots, a plunger acting upon the cutters for rigidly projecting the same exteriorly of the body through the slots and allowing retrograde movement on the shifting of the plunger in reverse directions.

6. In an underreamer, a cylinder, a plurality of cutters mounted in said cylinder and movable inwardly and outwardly, a plunger rod provided with a head adapted to engage said cutters to move the same and to hold them rigidly in projected position, a spring acting upon said plunger rod to move the same to hold the cutters in projected position, opposed trips movable parallel with each other pivoted to said cylinder and held normally projected by means of said spring, and a connection between said trips and said plunger rod whereby when the trips are moved inwardly by means of external pressure, the plunger head will be moved out of engagement with the cutters.

7. In an underreamer, a cylinder having a series of slots arranged circumferentially therearound, cutters movably mounted in said slots, a plunger rod provided with a head engaging said cutters to hold the same projected and rigid, said cylinder being provided with a diametrically extending slot above said cutters into which the plunger rod projects, a spring for normally moving said plunger head into engagement with said cutters, a cross bar at the upper end of said plunger rod, bell crank levers pivoted within said diametrically extending slot and having arms engaging said cross bar, trips pivotedly connected at certain ends to the opposite ends of said bell crank levers and having a link connection at their opposite ends to the walls of said slot, said spring normally tending to hold said trips in projected position, the movement of the trips in the opposite direction raising the plunger rod and disengaging the head thereof from the cutters.

8. In an underreamer, a cylinder provided with a series of circumferentially arranged longitudinal slots, cutters mounted in said slots, a plunger rod provided with a head engaging said cutters to hold the same normally projected, the upper portion of said cylinder being provided with a diametrically extending slot into which the upper end of the plunger rod projects, a cross bar fixed to the upper end of the rod and in said diametrically extending slot, a pair of trips, a pair of levers provided with spaced spacing bearings and having arms arranged upon opposite sides of said plunger rod and engaging the cross bar, the inner of said spacing bearings pivotally connecting the levers

intermediate their ends to said cylinder, the outer spacing bearings being pivotally connected to said trips, and links connecting the lower ends of the trips to the cylinder 5 whereby the same are held in parallel positions.

9. In an underreamer, a cylinder having a series of movable cutters arranged circumferentially therearound, pins interiorly of 10 the cylinder for the detachable connection of the cutters therewith, a plunger mounted within said cylinder and movable into engagement with said cutters to cause the same to project beyond the cylinder, and opposed 15 trips movable longitudinally of the cylinder parallel with each other downwardly and inwardly when engaged by the lower end of the well casing in drawing the underreamer upwardly through said casing, 20 whereby the plunger is controlled to release the cutters.
10. In an underreamer, a body, spaced 25 series of cutters radially arranged longitudinally in the body and movable laterally within and without the same, a plunger slidably fitted within said body and having

heads thereon adapted to engage the cutters for simultaneously projecting the series exteriorly of the body, and trip means movable parallel with the longitudinal extent 30 of the body for actuating said plunger to allow the cutters to move inwardly of the body or to rigidly hold the cutters projected therefrom.

11. An underreamer of the character described comprising a body, cutters detachably and movably mounted interiorly of said body to be extended radially exteriorly thereof into active position, means interiorly of the body for hanging the cutters therein, 40 mechanism operative upon the cutters to allow the retracting and the rigid projecting of the same within and without the body and also preventing accidental detachment of said cutters.

In testimony, that I claim the foregoing as my own, I have hereto affixed my signature in the presence of two witnesses.

FRANK A. HAUGH.
